UNITED STATES PATENT OFFICE.

ALEXANDER FRASER, OF RENFREW, ONTARIO, CANADA.

REPEATING DEVICE FOR TALKING-MACHINES.

1,327,816.

Specification of Letters Patent. Patented Jan. 13, 1920.

Application filed October 28, 1918. Serial No. 259,991.

To all whom it may concern:

Be it known that I, ALEXANDER FRASER, a subject of the King of Great Britain, and resident of Renfrew, in the Province of Ontario, Dominion of Canada, have invented certain new and useful Improvements in Repeating Devices for Talking-Machines, of which the following is a specification.

This invention relates to improvements 10 in a repeating device for talking machines, particularly machines of the so called Edison type, in which the tone horn extends below the records and swings about a pivot at its forward end, and the objects of the invention are to provide a simple and effective device by which a record may be caused to repeat, or cause to be automatically repeated any given number of times.

Further objects of the invention are generally to improve and simplify the construction of the device and enable the various parts to better perform the functions required of them. The device consists essentially of the improved construction herein- 25 after described in detail in the accompanying specification and drawings.

In the drawings:

Figure 1 is a plan portion of a talking machine embodying the present invention.

30 Fig. 2 is a sectional elevation.

Fig. 3 is a perspective detail of the repeating mechanism.

Fig. 4 is a side elevation showing a detail of the end of the swinging rack.

35 Fig. 5 is an end elevation of the device shown in Fig. 4.

Fig. 6 is a perspective detail of one of the repeating levers.

40 Fig. 7 is a plan view showing a detail of the device for stopping the machine after the record has been repeated a given number of times.

In the drawings, like characters of reference indicate corresponding parts in all the 45 figures.

Referring to the drawings, A represents the swinging tone horn mounted to swing about the vertical shaft 10, mounted upon a suitable cabinet B. The construction of the 50 talking machine itself with the method of operating the various parts thereof forms no part of the present invention, and only such parts of the machine are shown as are necessary to coöperate with the operation of the 55 parts of this invention. The usual driving mechanism is shown comprising a starter

member 11, worm gear 12, meshing with the worm 13 which drives the turn table (not shown). The shaft 15 connected to the worm 13 carries the enlarged worm 14 which meshes with gear 17 of a cross shaft 18 which carries the worm wheel 19, meshing with a ratchet 20 on the underside of the tone arm lever 21, which lever is pivoted to a bracket 22 forming the upper connection between 60 the tone arm A and the shaft 10. All of the foregoing parts are part of the well known mechanism of the Edison talking machine. In the operation of the talking machine when it is desired to disengage the 65 needle from the record and release the tone arm, the shaft 10 carrying the tone arm and lever 21 are adapted to be raised by a pivoted lever 23 having a cam shaft end 24 designed to bear against the surface of the 70 fixed support or cover plate 25 whereby when the lever 23 is pressed downwardly the shaft will be raised. I prefer, in my invention to augment the lever by means of a 75 spiral spring 26 surrounding the shaft 10 at 80 the bottom bearing against the lower connecting bracket 27 which is connected to the tone arm and comprises the shaft.

In regard to the present invention the adjustable tappet member 30 is provided, 85 carried by the swinging lever 21 and to provide for different sized records this lever has adjustable support. I have shown the lever with its upper end adjustably mounted on pin 31 held between brackets 32 and 33 90 which are formed on the U-shaped clamp 34 embracing one arm of the T-shaped end of the lever 21. The adjustment of the tappet member is indicated by means of a pointer 35 on the tappet member extending over a 95 scale 36 formed on the clamp 34.

It is not necessary to provide any means to hold the tappet in position for the reason that the lower end which carries a conveniently placed button 36^a, covered by 100 material such as rubber, is sufficiently below the pin 31 to cause a turning moment to be produced which will prevent sliding.

Mounted on the shaft 18 is a crank 40, having a projecting pin 41 adapted to engage the free end of a lever 42, which lever is centrally pivoted to the lower end of rod 43, the upper end of which rod is clamped to the fixed plate 25.

The opposite end of the lever 42, to that 110 engaged by the pin 41 is provided with a perforation through which the rod 44 ex-

tends; the inner end of the rod being connected to a clamp 45 which incloses the shaft 10 while the outer end is screw threaded having a nut 46 thereon, which engages the surface of the lever, the lever being held in outermost position on the rod by means of a spiral spring 47 which extends from the clamp 45 to the lever.

The position of the free end of the lever 10 is normally, slightly in advance of the pin 41 to the right as shown in Fig. 1, so that the pin may rotate and clear the lever. When the lever 21 swings over, the button 36^c on the tappet 30 will engage one end 15 of the lever 42 and push it sidewise to the left as shown in Fig. 5 into the path of the pin 41 thereby permitting the pin as it turns with shaft 18 to engage and depress the end of the lever moving the opposite end 20 upwardly. The upward movement of the lever 42 will be transmitted to the rod 47, clamp 45 and the shaft 10, and this shaft 10 will carry the tone arm A, upwardly lifting it until clear of the disk and when this takes 25 place the tone arm will swing to its original position, under the action of the tension spring 50 which is provided for that purpose extending between the bracket 51 on tone horn and eyelet 52 on the cabinet B. 30 The tone arm will reach its original position at the same time the rotation of the pin 41 causes the lever 42 to be moved on its pivot to return the tone arm to its normal position and the lever under pressure from 35 the spring 47 will turn about the axis of the pin 43 and resume its normal position; in this way the reproducer will be next lowered gently onto the record or disk.

Mechanism may be provided to cause the 40 repeating action to be terminated after a given number of repetitions of the record. The mechanism which I have devised comprises a disk 60 carrying the ratchet 61 and a tappet arm 62 which in a given position is 45 adapted to engage and actuate the operating lever 63 of the usual stopping mechanism of the phonograph, the disk 60 is mounted on a plate 64 which may conveniently be formed with a slot 65 to enable it to be inserted in position above the plate 25 on the 50 rod with the shaft 10 extending through the slot 65. The ratchet 61 is designed to be engaged by the spring pawl 66 carried by a lever 67 pivotally mounted on the pivot pin 55 68 which pivot pin connects the disk 60 with the plate 64, the lever 67 being operated from the lever 42 through the medium of a connecting rod 68^a extending from the end of the lever 42 and through the lever 67. It 60 will be therefore seen that each operation of the lever 42 will move the rod 68^a to swing the lever 67 and turn the ratchet 61 the distance of one tooth. When the lever 67 has been turned sufficiently to bring the lever 65 62 into engagement with the lever 63 the

automatic stopper will be thrown into operation. The disk 60 may be set in any desired position so that the stopper will be thrown into operation after the record has been played any given number of times.

It will be seen that the present invention provides a very simple and effective device which may be applied to any existing talking machine of the same construction and method of operation.

As many changes could be made in the above construction, and many apparently widely different embodiments of my invention within the scope of the claims, constructed without departing from the spirit or scope there, it is intended that all matter contained in the above specification and accompanying drawings, shall be interpreted as illustrative and not in a limiting sense.

What I claim as my invention is:

1. In a talking machine and in combination, a shaft, a swinging pivoted tone arm, a pivoted lever, feeding mechanism between the lever and the shaft from which the lever is adapted to be disengaged, a crank carried on the shaft, a pin thereon, a lever 42 adapted to be engaged by the pin, a tappet member carried by the tone arm carrying lever adapted to engage the free end of the last mentioned lever and carry the same laterally into position to be engaged by the tappet pin, means for connecting the opposite end of the lever to the tone arm, and means whereby the swing of the lever when engaged by the tappet pin is caused to raise the tone arm carrying lever.

2. In a talking machine and in combination, a shaft, a swinging pivoted tone arm, a lever, feeding mechanism between the lever and the shaft from which the lever is adapted to be disengaged, a crank carried on the shaft, a pin thereon, adapted to be engaged when the lever is moved laterally, a tappet member carried by the tone arm lever adapted to engage the free end of the last mentioned lever and carry the same laterally into position to be engaged by the tappet pin, means for connecting the opposite end of the lever to the tone arm, and means whereby the swing of the lever when engaged by the tappet pin is caused to raise the tone arm carrying lever, and said last mentioned means including a rod extending through the lever having a spring connected therewith adapted to return the lever to normal position.

3. In a talking machine and in combination, a shaft, a swinging pivoted tone arm, a lever, feeding mechanism between the lever and the shaft from which the lever is adapted to be disengaged, a crank carried on the shaft having a tappet pin adapted to engage the lever when moved laterally, a tappet member carried by the tone arm carrying lever adapted to engage the free end of

the last mentioned lever and carry the same laterally into position to be engaged by the tappet pin, means for connecting the opposite end of the lever to the tone arm, 5 and means whereby the swing of the lever when engaged by the tappet pin is caused to raise the tone arm carrying lever.

4. In a talking machine and in combination, a shaft, a swinging pivoted tone arm, 10 a lever, feeding mechanism between the lever and the shaft from which the lever is adapted to be disengaged, a crank carried on the shaft having a tappet pin adapted to engage the lever when moved laterally, a 15 tappet member carried by the tone arm carrying lever and carry the same laterally

into position to be engaged by the tappet pin, means for connecting the opposite end of the lever to the tone arm, and means whereby the swing of the lever when engaged by the tappet pin is caused to raise the tone arm carrying lever, and means for adjusting the position of the tappet carried by the tone arm carrying lever, said means comprising a rod on which the tappet is 20 mounted, brackets supporting the rod, a clamp connected to the brackets and comprising the tone arm carrying lever.

In witness whereof I have hereunto set my hand.

ALEXANDER FRASER.
